(57) **CLAIM**

The ornamental design for a bench, as shown and described.

DESCRIPTION

FIG. 1 is a front, top, and left side isometric view of a bench showing my new design;

FIG. 2 is a rear, bottom, and left side isometric view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The slats and portions of the frame of the bench are shown broken-away in FIGS. 1-4, 7, and 8, to indicate that a specific length of the bench forms no part of the claimed design.

1 Claim, 8 Drawing Sheets
